CARBURETOR

Scott F. Hunt, Meriden, Conn., assignor, by mesne assignments, to Niles-Bement-Pond Company, West Hartford, Conn., a corporation of New Jersey

Application August 11, 1943, Serial No. 498,151

7 Claims. (Cl. 261—41)

1

The present invention relates to carburetors, and especially to mixture control systems for carburetors associated with internal combustion engines used on aircraft.

An internal combustion engine of the type used on aircraft operates most economically on a lean fuel and air mixture. However, such a lean mixture will not produce the maximum power output of which the engine is capable. Furthermore, the use of a lean mixture under certain conditions, as when operating at high altitudes, for example, will cause the engine to overheat. It is, therefore, customary to provide, in connection with carburetors used on engines of this type, a manual control arrangement by which the fuel and air mixture supplied to the engine may be selectively set at either a rich or a lean value, depending upon the various flight conditions encountered. As a further control of the fuel and air mixture supplied to the engine, there is sometimes provided a valve which opens automatically under high load conditions to enrich the mixture, regardless of the position of the manual control. This additional valve is usually set to open at a certain value of load on the engine, as measured by the quantity of air or by the quantity of fuel flowing to the engine. For optimum economy and performance, it would be desirable to open this valve at a higher value of engine load when the mixture control is in its lean position and at a lower value of engine load when the mixture control is in its rich position. In previous carburetors, however, this enrichening valve has been set to open at a predetermined value of engine load, regardless of the setting of the manual mixture control. The load value at which this valve opens is a compromise between the load value which would be best when the mixture control is in lean position and the load value which would be best when the mixture control is in rich position.

It is therefore an object of the present invention to provide improved mixture control means for an aircraft carburetor.

Another object is to provide improved means for enriching the fuel and air mixture supplied by the carburetor of an aircraft engine in response to a condition indicative of the amount of load on the engine.

A further object of the present invention is to provide, in a carburetor equipped with a control member movable to a first position in which the carburetor supplies a lean mixture to the engine and to a second position in which the

2

carburetor supplies a rich mixture to the engine, improved means for enriching the mixture supplied to the engine in response to the variations in the engine load, which means operates at different load values depending upon the position of the mixture control member.

Other objects and advantages of the present invention will become apparent from a consideration of the appended specification, claims and drawing, in which

10 Figure 1 is a somewhat diagrammatic illustration of an aircraft carburetor embodying my invention, and

15 Figure 2 is a graphical illustration of the relationship between the fuel and air ratio and the air flow thru the carburetor of Figure 1.

20 In the drawing, there is shown a carburetor body portion 10 thru which air flows from an inlet 11 thru a passage 12 to an outlet 13. In flowing thru the passage 12, the air passes a Venturi restriction 14, a throttle 15, and a fuel discharge nozzle 16.

25 A second air passage connects the inlet 11 and the throat of the Venturi restriction 14. This second air passage may be traced from the inlet 11 thru a plurality of impact tubes 17, whose open ends project into the inlet 11, a vent ring passage 18 interconnecting the impact tubes 17, a conduit 20, an expansible chamber 21 in a pressure meter 22, a restriction 23, an expansible chamber 24 in the pressure meter 22, a conduit 28, a chamber 30, and a conduit 31 to the throat of Venturi restriction 14.

30 A bellows 32 is mounted in the chamber 30, and operates a valve 33 which controls the flow of air from the passage 28 into the chamber 30. The bellows 32 is preferably filled with nitrogen or other inert temperature responsive fluid, so that the position of valve 33 is determined by the temperature and pressure of the air in the chamber 30, and hence by the density of that air.

35 The valve 33 restricts the flow of air thru the second passage just described in such a manner that the pressure differential between chambers 21 and 24 is an accurate measure of the rate of mass air flow thru the passage 12. Errors due to changes in the density of the air with altitude and temperature and also those errors due 40 to the inherent limitations of a metering restriction of the Venturi type, are substantially eliminated by the operation of valve 33. This type of metering error compensation is more completely described and claimed in the co-pending application of Milton E. Chandler, Serial No. 490,281,

filed June 10, 1943, now Patent No. 2,393,144, issued Jan. 15, 1946.

The fuel passing thru the carburetor comes from a fuel pump or other source of fuel under pressure (not shown). From this source, the fuel passes thru a conduit 34, a fuel regulator unit 25, a conduit 35, a mixture control valve 36, a jet system 37, a conduit 38, a pressure regulator valve 40, and a conduit 41 to the discharge nozzle 16.

The pressure meter 22 includes a casing 42 which is separated by three flexible diaphragms 43, 44 and 45 into four expandable chambers 46, 24, 21 and 47. A sleeve 48 is attached to the central portions of the diaphragms 43, 44 and 45. An annular flange 50 on the interior of one end of the sleeve 48 acts as a valve, and cooperates with a tapered seat 51 formed on a post 52 extending thru the center of the sleeve 48. The internal diameter of the sleeve 48 is greater than the external diameter of the post 52, so that the position of the valve 50 relative to the seat 51 controls the flow of fluid thru the sleeve 48 between the chambers 46 and 47.

The fuel regulator unit 25 includes a housing 53 separated by a flexible diaphragm 54 into a pair of expandable chambers 55 and 56. The diaphragm 54 supports at its central portion a valve 57. The valve 57 controls the flow of fluid between the conduit 34 and the chamber 56, which is directly connected with conduit 35. The valve 57 is balanced against variations in inlet pressure. The position of valve 57 is determined by the difference between the pressures in the chambers 55 and 56, and by the compression of a spring 58, which urges the valve 57 in an opening direction. The chambers 55 and 56 are connected by a restricted passage 60.

The mixture control valve 36 includes a disc valve member 61 fixed on a shaft 62 which may be rotated by means not shown, as, for example, a manual lever. The disc valve member 61 is designed to control the flow of fuel from conduit 35 thru a chamber 63 to conduits 64 and 65. When the disc valve 61 is in the position shown in the drawing, the fuel is free to enter both conduits 64 and 65. As the shaft 62 is rotated, the disc valve 61 may be moved to another position wherein it permits the flow of fuel from chamber 63 only thru conduit 65. If desired, the disc valve 61 may also be designed so that in certain angular positions, it completely cuts off the flow of fuel from the conduit 35.

The jet system 37 includes a pair of jets or restrictions 66 and 67 which receive fuel thru the conduit 65, and a jet 68 which receives fuel thru the conduit 64. Fuel flowing thru the jets 67 and 68 also passes thru a jet 70 before flowing out of the jet system 37 into the conduit 38. A poppet valve 71 is positioned in the jet 67 so as to be urged toward open position by the pressure differential which causes the fuel flow thru the jet. A spring 72 biases the poppet valve 71 to closed position. A poppet valve 73 is positioned in the jet 68 so as to be urged in an opening direction by the pressure differential which causes the fuel flow thru that jet. A coil spring 74 biases the valve 73 to closed position. The poppet valve 73 is apertured as at 75, so that even when the valve 73 is seated, a small amount of fuel may pass thru the jet 68 and the apertures 75. It will be readily apparent that a fixed restriction in parallel with the jet 68 may be used instead of the apertures 75 in the valve 73, if desired.

The pressure regulator 40 includes a casing 76

separated by a diaphragm 77 into a pair of expandable chambers 78 and 80. The diaphragm 77 carries a valve 81 at its center. The valve 81 controls the flow of fuel from chamber 80, which is connected to conduit 38, to the outlet conduit 41. The valve 81 is balanced against changes in outlet pressure, so that the position of valve 81 is determined by the difference in pressures between the chambers 78 and 80, and by the tension 10 of the spring 82 which biases the valve 81 toward closed position. The chamber 78 is connected thru a conduit 82 to the vent ring 18. The pressure in chamber 78 is small as compared to the sum of that pressure and the strength of spring 15 82. Therefore the pressure in chamber 78 has only a small controlling effect on the position of valve 81. The connection of chamber 78 thru conduit 82 to vent ring 18 serves as a vent for the chamber 78 so as to permit ready movement 20 of the diaphragm 77 in response to variations in pressure in the chamber 80, and also to vary the pressure in chamber 78 according to changes in barometric pressure.

Operation

A portion of fuel entering the fuel regulator 25 passes thru chamber 56, restriction 60, chamber 55, a conduit 83, chamber 48 of pressure meter 22, thru the center of sleeve 48, chamber 47, and a conduit 84 to chamber 80 of the pressure regulator 40.

The quantity of fuel entering the carburetor is measured by the jet system 37, and is controlled by varying the pressure differential across that system. The pressure downstream from the jet system 37 is maintained substantially constant by the pressure regulator 40, while the pressure upstream from the jet system 37 is controlled by the fuel regulator 25. The fuel regulator 25 is in turn controlled by the pressure meter 22.

The difference in pressure between chambers 21 and 24 of the pressure meter 22 is a measure of the quantity of air entering the carburetor, as previously described. This differential pressure acts on the sleeve 48 in a direction tending to move the valve 50 against the seat 51. This pressure differential is opposed by the pressure in chamber 46, and is aided by the pressure in chamber 47. The pressure in chamber 47 is the same as that in chamber 80 of pressure regulator 40, and hence is the same as the pressure on the downstream side of the jet system 37. The pressure in chamber 46, on the other hand, is the same as that in chamber 55 of fuel regulator 25. Since the latter chamber is connected to the upstream side of the jet system 37 thru the fixed restriction 60, it may be seen that the pressure in chamber 55 is a measure of the pressure on the upstream side of the jet system 37. Therefore, the pressure meter 22 controls the pressure in chamber 55 in accordance with the unbalance between a differential pressure indicative of the quantity of air entering the carburetor and a second differential pressure indicative of the quantity of fuel entering the carburetor. When these two differential pressures become unbalanced, the pressure meter 22 operates to vary the pressure in chamber 55 in a direction to restore the balanced condition, and at the same time varies the flow thru the fuel regulator unit 25 so as to maintain the pressure differential across the jet system 37 proportional to the quantity of air entering the carburetor.

When the mixture control valve 61 is in the position shown in the drawing both the conduits

64 and 65 may receive fuel from the chamber 63. This is the rich position of valve 61. When the valve 61 is in this position, fuel may flow thru all three of the jets 66, 67 and 68. The relationship between the air flow and the fuel and air ratio under these conditions is illustrated by the characteristic C in Fig. 2. At low values of air flow, the pressure differential across the jet system 37 as controlled by fuel regulator 25, is also low. The springs 72 and 74 are strong enough to maintain their associated poppet valves 71 and 73 closed under these conditions. Therefore the fuel flow is determined by the cross-sectional area of jet 66 and the apertures 75 thru the poppet valve 73.

If it is now assumed that the throttle is opened wider so that the air flow increases, the pressure differential across the jets will be likewise increased by the action of the fuel regulator 25. When the air flow exceeds a predetermined value, which may be that value indicated by the ordinate A in Figure 2, the pressure differential across jet 68 becomes sufficient to overcome the spring 74. The poppet valve 73 then opens, increasing the ratio of fuel to air in the mixture supplied to the engine. If the air flow continues to increase until it reaches a value such as that indicated by the ordinate B in Figure 2, the pressure differential across jet 67 becomes sufficient to overcome spring 72 which is stronger than spring 74, thereby opening the poppet valve 71 and further increasing the fuel to air ratio.

When the mixture control valve 61 is in its lean position, the conduit 64 is closed, and the conduit 65 remains open. Under those conditions, no fuel flows thru jet 68. The relationship between the fuel and air ratio and the air flow then obtained is illustrated by the characteristic D in Figure 2. There it may be seen that as the air flow increases the fuel to air ratio remains substantially constant until an air flow indicated by the ordinate B is reached. Then the pressure differential across jet 67 opens the poppet valve 71, acting against spring 72, and increasing the fuel to air ratio.

It may therefore be seen that I have provided a mixture control system wherein the fuel to air ratio is maintained at a low economical value until a very high air flow is encountered when a manually operable mixture control is in a lean position, but that the fuel to air ratio is increased at a lower value of air flow when the manually operable mixture control is in its rich position.

While I have shown and described a preferred embodiment of my invention, other modifications thereof will occur to those skilled in the art, and I therefore intend that my invention shall be limited only by the appended claims.

I claim as my invention:

1. A fuel supply system for an internal combustion engine, comprising a first main conduit for conveying combustion air to said engine, a second main conduit for conveying fuel to said engine, first and second parallel branch conduits connected in series with said second main conduit, a mixture control valve located at a junction of said parallel branch conduits and said second main conduit, said mixture control valve being movable between a first position wherein only said first parallel branch conduit is opened to the flow of fuel and a second position wherein both of said parallel branch conduits are opened to the flow of fuel, first and second fixed metering restrictions in said first and second parallel branch conduits, respectively, means responsive to the rate of flow of air thru said first main conduit for

regulating the fuel pressure differential across said restrictions to control the rate of flow of fuel therethru, said pressure differential regulating means, said restrictions and said mixture control valve cooperating when said mixture control valve is in said first position to maintain a first predetermined fuel-to-air ratio and when said mixture control valve is in said second position to maintain a second predetermined fuel-to-air ratio greater than said first ratio, first and second enrichment valves connected in parallel with said first and second restrictions, respectively, each said enrichment valve being acted upon in an opening sense by said fuel pressure differential, and first and second springs associated with said first and second enrichment valves, respectively, to bias said valves toward closed position, said first spring being stronger than said second spring, said valves and springs cooperating with said pressure differential regulating means to increase the fuel-to-air ratio above said first predetermined value at a first fuel pressure differential value when said mixture control valve is in said first position and to increase the fuel-to-air ratio above said second predetermined value at a second lower fuel pressure differential value when said mixture control valve is in said second position.

2. A fuel supply system for an internal combustion engine, comprising a first main conduit for conveying combustion air to said engine, a second main conduit for conveying fuel to said engine, first and second parallel branch conduits connected in series with said second main conduit, a mixture control valve located at a junction of said parallel branch conduits and said second main conduit, said mixture control valve being movable between a first position wherein only said first parallel branch conduit is opened to the flow of fuel and a second position wherein both of said parallel branch conduits are opened to the flow of fuel, first and second fixed metering restrictions in said first and second parallel branch conduits, respectively, means responsive to the rate of flow of air thru said first main conduit for regulating the fuel pressure differential across said restrictions to control the rate of flow of fuel therethru, said pressure differential regulating means, said restrictions and said mixture control valve cooperating when said mixture control valve is in said first position to maintain a first predetermined fuel-to-air ratio and when said mixture control valve is in said second position to maintain a second predetermined fuel-to-air ratio greater than said first ratio, enrichment valve means connected in parallel with said restrictions, said enrichment valve means being acted upon in an opening sense by said fuel pressure differential, and spring means for biasing said enrichment valve means toward closed position, and means to vary a force acting on said enrichment valve means in a valve-opening sense upon movement of said mixture control valve from said first to said second positions, said enrichment valve means and said force varying means cooperating with said pressure differential regulating means to increase the fuel-to-air ratio above said first predetermined value at a first fuel pressure differential value when said mixture control valve is in said first position and to increase the fuel-to-air ratio above said second predetermined value at a second lower fuel pressure differential value when said mixture control valve is in said second position.

3. A fuel supply system for an internal combus-

tion engine, comprising a first main conduit for conveying combustion air to said engine, a second main conduit for conveying fuel to said engine, first and second parallel branch conduits connected in series with said second main conduit, a mixture control valve located at a junction of said parallel branch conduits and said second main conduit, said mixture control valve being movable between a first position wherein only said first parallel branch conduit is opened to the flow of fuel and a second position wherein both of said parallel branch conduits are opened to the flow of fuel, first and second fixed metering restrictions in said first and second parallel branch conduits, respectively, means responsive to the rate of flow of air thru said first main conduit for regulating the fuel pressure differential across said restrictions to control the rate of flow of fuel therethru, said pressure differential regulating means, said restrictions and said mixture control valve cooperating when said mixture control valve is in said first position to maintain a first predetermined fuel-to-air ratio and when said mixture control valve is in said second position to maintain a second predetermined fuel-to-air ratio greater than said first ratio, an enrichment valve connected in parallel with one of said restrictions, said enrichment valve being acted upon in an opening sense by the pressure drop across said second restriction, and a spring for biasing said enrichment valve toward closed position, said enrichment valve cooperating with said pressure differential regulating means only when said mixture control valve is in said second position to increase the fuel-to-air ratio above said second predetermined value at a predetermined fuel pressure differential value.

4. A fuel supply system for an internal combustion engine, comprising a first main conduit for conveying combustion air to said engine, a second main conduit for conveying fuel to said engine, first and second parallel branch conduits connected in series with said second main conduit, a mixture control valve located at a junction of said parallel branch conduits and said second main conduit, said mixture control valve being movable between a first position wherein only said first parallel branch conduit is opened to the flow of fuel and a second position wherein both of said parallel branch conduits are opened to the flow of fuel, first and second fixed metering restrictions in said first and second parallel branch conduits, respectively, means responsive to the rate of flow of air thru said first main conduit for regulating the fuel pressure differential across said restrictions to control the rate of flow of fuel therethru, said pressure differential regulating means, said restrictions and said mixture control valve cooperating when said mixture control valve is in said first position to maintain a first predetermined fuel-to-air ratio and when said mixture control valve is in said second position to maintain a second predetermined fuel-to-air ratio greater than said first ratio, enrichment valve means connected in parallel with said restrictions, said enrichment valve means being movable in response to the pressure in said second branch conduit between said mixture control valve and said second restriction, spring means for biasing said enrichment valve means toward closed position, said mixture control valve means being effective upon movement to said second position to vary said pressure in an enrichment valve opening sense, said enrichment valve means cooperating with said pressure differential regulat-

ing means to increase the fuel-to-air ratio above said first predetermined value at a first fuel pressure differential value when said mixture control valve is in said first position and to increase the fuel-to-air ratio above said second predetermined value at a second lower fuel pressure differential value when said mixture control valve is in said second position.

5. A charge forming device for an internal combustion engine, comprising a conduit for combustion air flowing toward said engine, means for controlling the flow of air thru said conduit, a conduit for fluid fuel flowing toward said engine, means for controlling the flow of fuel thru said fuel conduit, means for coordinating the operation of said fuel flow control means and said air flow control means to maintain a predetermined fuel-to-air ratio, first means associated with said coordinating means for varying said ratio, an operator for said first means movable between a first position wherein said coordinating means and said ratio varying means cooperate to maintain a first predetermined ratio and a second position wherein said coordinating means and said ratio varying means cooperate to maintain a second greater ratio, and second means including a plurality of successively opening fuel valves in said first means for varying said ratio to increase said ratio above said first value when said operator is in said first position and the rate of air flow exceeds a first predetermined value, and to increase said ratio above said second value when said operator is in said second position and the rate of air flow exceeds a second value lower than said first value.

6. Fluid flow controlling apparatus, comprising first and second parallel conduits leading from a common inlet to a common outlet, first and second restrictions in said first and second conduits, respectively, a selector valve in series with said conduits and movable between a first position wherein flow is permitted only thru said first conduit and a second position wherein flow is permitted thru both said conduits, first and second by-pass conduits connected in parallel with said first and second restrictions, respectively, first and second pressure responsive valves in the respective by-pass conduits, said pressure responsive valves being movable in an opening direction in response to the fluid pressure differential across said restrictions, first and second springs biasing said first and second valves, respectively, toward closed position, said second spring being weaker than said first spring so that said second valve opens at a lower value of fluid pressure differential than said first valve.

7. Fluid flow control apparatus, comprising a main conduit, a pair of parallel branch conduits connecting two spaced portions of said main conduit, a selector valve at one of the junctions of said branch conduits with said main conduit, said selector valve being movable between a first position wherein only one of said branch conduits is open and a second position wherein both of said branch conduits are open, a metering restriction in each of said branch conduits, said selector valve being effective upon movement to said first and second positions to establish respectively first and second relationships between the fluid pressure differential between said portions of said main conduit and the quantity of fluid per unit of time therethru, passage means arranged for flow parallel to said branch conduits, valve means in said passage means subject to said fluid pres-

sure differential, said differential acting on said valve means in an opening sense, spring means biasing said valve means to closed position, and means including said selector valve to vary a force acting on said valve means in a valve-opening sense upon movement of said selector valve from said first to said second positions, so that said valve means commence to open when said selector valve is in said first position at a first predetermined value of said pressure differential and when said selector valve is in said second position at a second lower value of said pressure differential.
